Division of application Serial No. 378,122, February 10, 1941. Continuation of application Serial No. 416 002, October 22, 1941. This application March 3, 1944, Serial No. 524,940

12 Claims. (Cl. 74—289)

1

This application is a continuation of my co-pending application, Serial No. 416,002, filed October 22, 1941, for Clutch mechanism, and a division of my co-pending application, Serial No. 378,122, filed February 10, 1941, for Potato Diggers.

This invention relates generally to self-interrupting clutch mechanisms and more particularly to power actuated lifting clutch means for raising and lowering the operating part or parts of an agricultural implement or the like.

The object and general nature of the present invention is the provision of a self-interrupting clutch which includes planetary gearing and associated control means therefor.

An additional feature of the present invention is the provision of improved self-interrupting clutch mechanism in which two driven parts are connected through planetary gear units with a continuously rotatable driving part, and in which a suitable control is arranged normally to hold one of the driven parts against rotation but movable into a position to lock the other against rotation to drive the first mentioned driven part. In this connection, it is another feature of this invention to provide means for automatically restoring the control means to a position in which the operative driven part is locked in non-rotating position.

These and other objects and advantages of the present invention will be apparent to those skilled in the art after a consideration of the following detailed description, taken in conjunction with the accompanying drawings.

In the drawings:

Figure 1 is a side view of a self-interrupting clutch mechanism incorporating the present invention, the clutch being shown as connected to operate a generally longitudinally shiftable connecting rod with which may be associated any suitable part or parts to be actuated thereby;

Figure 2 is a sectional view taken along the line 2—2 of Figure 1;

Figure 3 is a fragmentary side view, showing the trip or control lever in its operating position for causing the clutch to deliver power to the part or parts to be actuated thereby;

Figure 4 is a fragmentary view showing the means for limiting the outward movement of the clutch control trip lever; and

Figure 5 is a fragmentary side view, similar to Figure 3, showing the trip lever in an intermediate position.

Referring now to the drawings, the self-interrupting clutch mechanism of the present invention

2

is indicated in its entirety by the reference numeral 98 and for purposes of illustration has been shown as mounted on a supporting plate 101 carried by a frame bar 6a, which members form a part of a potato digger frame 4. As explained in more detail in my co-pending application identified above, the potato digger includes power driven mechanism for driving the elevator, and in addition power is delivered by such mechanism through a drive chain 96 to the clutch mechanism 98, the chain 96 being trained around a sprocket member 97 (Figure 2) which forms a part of or is connected to the driving member of the clutch. Thus, the sprocket 97 is continuously driven from the power means of the potato digger during all times that the outfit is in operation.

Referring now more particularly to Figures 1 and 2, the supporting plate 101, which is mounted in any suitable manner on the inside frame bar 6a of the frame 4, receives a bolt 102 by which a stationary bushing 103 is firmly secured in place. The drive sprocket 97 is journaled for rotation on the bushing 103 and is provided with a hub 104 in one end of which gear teeth 105 are formed. The hub 104 thus forms the driving gear of the clutch unit 98. A rotatable housing 106 is mounted on the hub 104 and is provided with a central hub section 107 which at two diametrically opposite points is slotted out, as at 108, to receive the larger gear section 109 of a compound planet gear, indicated in its entirety by the reference numeral 110. If desired, I may employ only one gear member 110, but two may be used, as shown in Figure 2. Each gear member 110 is mounted for rotation on a stud 111 fixed to the rotatable housing 106 in any suitable manner, as by being threaded into the radial web portion thereof. A second rotatable housing 115 is provided with a hub 116 and is rotatably journaled on the stationary bushing 103. The hub 116 is received within the laterally outer end of the hub 107, whereby all of these parts are maintained in accurate concentric relation.

The rotatable housing 115 is formed peripherally as an internal ring gear, indicated at 119, and is provided with teeth 120 which mesh with the other gear section 121 of each of the compound planet gears 110. Thus, as best shown in Figure 2, the clutch mechanism 98 includes planetary gearing, of which the hub 104 is the driving member and the two rotatable housings 106 and 115 are driven members, the latter being driven by means of the planetary gears 110. As will be

readily understood, either of the members 106 and 115, if held against rotation, may serve as the reaction member by which the gears 110 will drive the other member. As described above, the hub 104 with the teeth 105 serves as the sun gear, the gears 110 serve as the planet gears of which the member 106 is the planet gear carrier, and the other rotatable housing 115 serves as the ring gear.

As will be understood by reference to my above-identified parent application, the rotatable housing 115 is link-connected with the shovel unit or units of the potato digger for the purpose of raising and lowering them, but so far as the present invention is concerned the member 115 may be connected to any part or parts that it is desired to operate. In potato diggers, as well as in the majority of other agricultural implements, the power lift clutch is usually connected with some part to be raised, as into a transport position, and held in that position until it is desired to lower the same, but usually the clutch mechanism is not required to hold the part or parts in a lowered position since they are usually constrained to occupy a lowered position either by gravity or by the action of the soil or other load acting against the part or parts. However, as will be referred to below, the self-interrupting clutch mechanism 98 may be constructed, if desired, so as to hold the load driven by the clutch mechanism in either of its positions, or, if desired, the load may be moved through a cycle that includes movement from one position to another and then from the latter position back to the first position. For controlling the clutch mechanism 98 I therefore provide suitable control means for locking one or the other of the members 106 and 115 against rotation and releasing the other member to permit it to rotate, whereby a positive driving connection is established through the clutch mechanism, both during movement of the load in one direction and movement of the load in its other direction. Thus, when the clutch mechanism 98 is incorporated in a potato digger to control the shovel or shovels thereof, a driving connection is established through the clutch mechanism, both during the raising and lowering movements of the shovel or shovels, as described in detail in my co-pending parent application mentioned above.

The clutch controlling means is best shown in Figures 1, 3 and 4, and referring now to these figures it will be seen that the rotatable housing member 106 is provided with a radial flange 126 which is formed with a plurality of notches or scallops 127. As will also be seen from Figure 2, the radial flange 126 is offset axially so as to lie in a plane closely adjacent a flange 130 that is formed on the other rotatable housing member 115. The member 115 is provided on the flange 130 with a stop lug or cam 132 and an adjacent trip lug or cam 133. Cooperating with the notches 127 and the lugs 132 and 133 is a trip or control lever 136. The lever 136 is mounted for rocking movement on a stud 137 fixed in any suitable manner to the supporting plate 101. It will be noted, particularly from Figure 1, that the lug or lugs 132 do not extend radially outwardly beyond the bottom of the notches 127.

The trip lever 136 is of particular construction. At one side of the axis defined by the journal portion 138 receiving the lug 137 the lever 136 carries a lug 139 which lies in the plane of the flange 130 on the rotatable housing member 115, and at the other side of the axis of the lever 136

is a lug 140 that extends substantially the axial length of the journal section 138 and is in a position to engage any one of the notches 127 formed in the flange 126 of the rotatable housing member 106. A lug 141 is carried by the trip lever 136 and serves as a stop limiting the outward movement of the lever (Figures 3 and 4), as will be explained below. As best shown in Figure 5, the relation between the lugs 139 and 140 is such that only one may be engaged with the associated lugs 132 and notches 127 at any one time, for after the lug 139 has been moved to clear the lug 132 and then rides along the flange 130, the lug 140 on the lever 136 clears the notches 127, as best shown in Figure 5. A suitable spring 142 is anchored at one end, as at 143, to the supporting plate 101 and at the other end is connected with the lever 136, biasing the same for movement into the position shown in Figure 1, in which the lug 139 engages the lug 132 on the member 115, thereby holding the latter against rotation while the other lug 140 on the lever 136 clears the notches 127, thereby permitting the member 106 to rotate, it being remembered that the part 106 serves as the planet gear carrier for the planetary gearing of which the members 106 and 115 are parts.

The driven member 115 of the clutch mechanism 98 is connected to actuate the load to be controlled thereby through an actuating link 149, the member 115 carrying a crank pin 148 which receives the rear end of the link 149, and as best shown in my above-identified parent application, the forward end of the link 149 is connected through suitable means to the raising and lowering mechanism for the potato digger shovel or shovels. Briefly, the connections are such that the rearward movement of the link 149, that is, to the left as shown in Figure 1, will raise the shovel or shovels and forward movement of the link 149 will lower the shovel or shovels, provided they are permitted to lower by depth adjusting means which forms a part of the potato digger. So far as the present invention is concerned, it may be considered that generally horizontal movement of the link 149 moves the load or other parts to be actuated from one position to another. In the construction shown in Figure 1, it will be noted that there is only one pair of lugs 132, 133, and in this case the clutch mechanism 98 is thus adapted to raise a load, such as the shovel of a potato digger, into a position in which a load constantly exerts a tendency to move back to its other position, which is prevented by the engagement of the lever 136 with the lug 132 as shown in Figure 1, but in the other position of the load it exerts no tendency to move out of that position, at least in the other direction, being held in that position by gravity or some other means. However, the clutch mechanism 98 may be provided with two sets of lugs 132, 133 so that the load may be positively held in any position. For example, Figure 3 shows the crank pin 148 moved through substantially 180 degrees and with the member 115 provided with another set of lugs 132, 133 which occupy substantially the same position, relative to the control lever 136, that the lugs 132, 133 shown in Figure 1 occupy.

The operation of the clutch mechanism and its control is substantially as follows.

Assuming that the clutch actuated link 149 is connected to a load which is adapted to be raised and lowered, such as the shovel or other tool of an agricultural implement, the normal transport or raised position of the parts is shown in Figure

1, the weight or tendency of the load, acting through the link 149, to return to its lowered position tending to rotate the member 115 in a clockwise direction, as viewed in Figure 1, but this movement is restrained by the engagement of the lug 132 with the lug 139 on the control lever 136. It will be noted that to secure this action, the parts are so arranged that the crank pin 143 is slightly above the axis of the supporting bolt 102, which defines the axis of rotation of the driven clutch member 115. The spring 142 serves to hold the control lever 136 in the position shown with the lug 139 engaging the lug 132 on the member 115. When the lug 139 on the control lever 136 engages the lug 132 on the member 115, the other lug 140 on the control lever 136 is in a position clearing the notches 127. Therefore, since the driving sprocket 97 and associated sun gear 105 are rotated continuously, this rotation is transmitted by the planet gears 110 to the planet gear carrier member 106, acting against the locked member 115 which is stationary. The sprocket gear 97 is normally driven in the direction of the arrow *a* shown in Figure 1, and when the member 115 is locked against rotation, the notched member 106 is driven idly in the same direction.

When it is desired to lower the load by permitting the link 149 to move to the right (Figure 1) into the position shown in Figure 3, or actually to force the link 149 to move from the position of Figure 1 to the position of Figure 3, the operator pulls on the cable 165, thereby swinging the control lever 136 to the position shown in Figure 3, in which the lug 139 is moved away from the lug 132 on the member 115 to which the lifting link 149 is connected, at the same time moving the lug 140 into engagement with one of the notches 127 and thereby locking the latter against rotation in either direction. It will be noted that both of the lugs 139 and 140 are rounded, and the relation of the parts is such that by the time the lug 140 engages in one of the notches 127 far enough to prevent the member 106 from rotating, the other lug 139 is in a position permitting the lug 132 to pass the lug 139. Thus, as soon as the lug 140 locks the member 106 against rotation, the drive is then transmitted through the planetary gearing to the member 115, this member rotating in a clockwise direction, as indicated by the arrow *b* in the lower portion of Figure 1. The weight of the load, in the event that the load driven by the clutch mechanism 98 is one that is raised, as for example the digger shovels of a potato digger, may also tend to turn the member 115 in the direction of arrow *b*, but if the operator retains his hold on the rope 165, holding the lug 140 in engagement with the member 106, the load connected with the link 149 will be permitted to move no faster than the member 115 is driven. However, if desired, the operator may release the cable 165 a moment after the trip lever 136 has been operated to release the lug 132 in the raised position of the parts (Figure 1), in which case the load may then move downwardly under the action of gravity and the lug 139 will merely ride along the flange 130 with the lug 140 just clearing the notches 127, as best shown in Figure 5. After the load reaches its lowered position, the member 106 merely idles and the member 115 remains stationary. As mentioned above, where the load or other part or parts to be actuated by the clutch 98 is of the type that tends to remain in a lowered position, there is no need for the second set of

6
lugs 132, 133 shown in Figure 3, but if the load or other part or parts actuated by the clutch 98 must be held positively in a lowered or second position, then the lugs 132, 133 shown in Figure 3 should be provided. From Figure 3 it can be seen that when the operator releases the cable 165 and permits the control lever 136 to move back into the position indicated in Figure 1, the lug 139 will engage the lug 132 (Figure 3) and prevent any tendency for the link 149 to move to the left (Figure 3) from driving the clutch member 115.

When subsequently it is desired to move the link 149 from the position shown in Figure 3 back to the position shown in Figure 1, all the operator has to do is to pull the cable 165, which again moves the control lever 136 into the position shown in Figure 3 which moves the lug 140 into one of the notches 127 and locks the member 106 against rotation, whereupon the member 115 will be driven in a clockwise direction (Figure 3), which moves the link 149 to the left, thus moving the load connected with the link 149 in a corresponding direction. The reaction of the load is transmitted by the planetary gearing to the member 106, tending to cause the same to rotate in a counter-clockwise direction. However, this is resisted by the engagement of the lug 140 in one of the notches 127. The operator may therefore release his hold on the cable 165, the reaction exerted through the member 106 thus holding the lever 136 in the position shown in Figure 3. In this position, the lug 141 bears against the shoulder 144 (Figure 2) on the member 106, thus limiting the clockwise movement of the trip lever 136 under the counterclockwise reaction of the member 106. The continued rotation of the sprocket 97 therefore continues the clockwise rotation until the lug 133 comes into engagement with the lug 140. At this point the continued rotation of the member 115 therefore acts positively to swing the trip lever 136 in a counterclockwise direction, moving the lug 140 out of engagement with the member 106 and swinging the lug 139 into a position to reengage the lug 132, thus positively swinging the trip lever 136 from the position shown in Figure 3 back to the position shown in Figure 1. The parts are so arranged, that by the time this occurs the pivot 148 passes to a point above the axis of rotation of the member 115, defined by the pivot bolt 102, so that the tendency of the load to rotate the member 115 in a clockwise direction (Figure 1) holds the lug 132 against the lug 139 on the trip lever 136, thereby locking the rotatable member 115 in the position shown in Figure 1.

Although the clutch mechanism just described finds its greatest usefulness in potato diggers and other agricultural implements, the clutch mechanism of the present invention obviously may have other uses. For example, if the load is such as to tend to rotate the driven member 115 continuously, or at least through a full revolution, rather than only through approximately a half revolution as in the instant construction, and where the driven member 115 carries only one set of lugs 132, 133, the clutch will automatically disengage after a complete revolution. If it should be desired to provide a self-interrupting clutch which positively disengages, say, every 180 degrees, then two sets of lugs 132, 133 would be provided at points diametrically opposite the lugs 132, 133 shown in Figure 1. It is to be noted that the lugs 132, 133 in Figure 3 as shown in a position on the member 115 diametrically

70
75

opposite the position of the lugs 132, 133 of Figure 1. As will be apparent, more than two sets of lugs may be employed and they may be spaced about the periphery of the driven member 115 at any desired spacing so as to secure the desired angular rotation before interruption. It is an important feature of a clutch of the type described that the reaction of the transmission of the driving force is utilized for holding the spring biased trip lever in a position engaging the member 106 until the trip lever 136 is actually forced back into a position holding the driven member against further rotation.

It will be understood that while I have shown the self-interrupting planetary clutch mechanism as incorporated in a two-row potato digger, such mechanism may be employed in other implements, especially those in which it is desired that both the raising and lowering movements be controlled by the power connections. It will also be seen that the driven member 115 may have one, two or more pairs of controlling lugs 132 and 133 depending upon the extent of revolution it is desired that the member 115 shall make before its movement is automatically interrupted. Thus, while I have shown and described above the preferred structure in which the principles of the present invention have been incorporated, it is to be understood that my invention is not to be limited to the particular details shown and described above, but that, in fact, widely different means may be employed in the practice of the broader aspects of my invention.

What I claim, therefore, and desire to secure by Letters Patent is:

1. A self-interrupting clutch mechanism for agricultural implements or the like, comprising three rotatable coaxially disposed members, means for driving one of said members, planetary gearing means reacting against either of the other two members for transmitting power to the other of said two members, and a part having sections engageable with said two members and movable from one position, in which one of said sections holds one of said two members against rotation and the other of said sections releases the other of said two members for rotation, to a second position in which the other section holds said other of said two members against rotation and said one section releases said one of said two members for rotation, one of said members being provided with means engageable with said part for moving it into one of said positions.

2. A self-interrupting clutch mechanism for agricultural implements or the like, comprising a pair of rotatable notched members, driving means therefor including gearing whereby either of said members is rotated when the other is held against rotation, a lever pivotally mounted adjacent said members and having means at opposite sides of the pivot axis of the lever engageable, respectively, with the notches of said members, spring means biasing said lever for movement to a position in which one of said members is held against rotation while the other is permitted to rotate, means for moving said lever into its other position releasing said one member and locking the other member against rotation, and a lug on said one member operable to force said lever back into said one position after a predetermined extent of rotation has taken place.

3. A self-interrupting clutch mechanism for agricultural implements or the like, comprising

three rotatable coaxially disposed members, means for driving one of said members, planetary gearing means reacting against either of the other two members for transmitting power to the other of said two members, means engageable with said two members and movable from one position, in which said means holds one of said two members against rotation and releases the other of said two members for rotation, to a second position in which said means holds said other of said two members against rotation and releases said one of said two members for rotation, and means on one of said two members for controlling the position of said movable means.

4. A self-interrupting clutch mechanism comprising three rotatable coaxially disposed members, means for driving one of said members, planetary gearing means reacting against either of the other two members for transmitting power to the other of said two members, means movable between two positions and engageable with said two members, said means being movable from one position, in which said means engages and holds one of said two members against rotation and releases the other of said two members for rotation, to a second position in which said means engages and holds said other of said two members against rotation and releases said one of said two members for rotation, and means responsive to the rotation of one of said two members through a predetermined extent for controlling the position of said movable means.

5. A self-interrupting clutch mechanism for agricultural implements or the like, comprising a pair of rotatable notched members, driving means therefor including gearing whereby either of said members is rotated when the other is held against rotation, a lever pivotally mounted adjacent said members and having means at opposite sides of the pivot axis of the lever engageable, respectively, with the notches of said members, means for moving said lever into one position about said pivot axis to engage one of said notched members and release the other member for rotation, and means on said rotatable member for moving said lever back into engagement with said one member.

6. In clutch mechanism, a pair of members, connections associated with said members whereby when one of said members is held against rotation the other member is driven, each of said members having means serving as lugs, a lever mounted for movement into engagement with the lugs on said other member to lock it against rotation and adapted to be engaged with the lugs on said one member so as to hold it against rotation and cause the other member to be driven, and means on said other member for causing said lever to be moved out of engagement with said one member after it has been moved into engagement with said one member to cause rotation of said other member.

7. Clutch mechanism of the self-interrupting type, comprising three relatively rotatable members, planet gear means carried on one of said members and geared to the other two members, one of said members constituting a driving member and the other of said members constituting driven members, one of said driven members being notched and the other of said driven members having a locking lug, a lever mounted for movement into engagement with said lug for locking said other member against rotation, biasing means normally holding said lever in a first

position engaging said lug, a lug on said lever adapted to engage the notched portion of said one driven member so as to lock it against rotation when said lever is moved into a second position releasing the lug on said other driven member, whereby power may be delivered to the latter to rotate the same, and a restoring lug on said other driven member adapted during rotation to engage said lever and automatically move it back into said first position and interrupt the delivery of power to said other driven member.

8. In clutch mechanism, a pair of rotatable members, connections associated with said members whereby when one of said members is held against rotation the other member is driven, a lever mounted for movement into engagement with said other member to lock it against rotation and cause said one member to be driven and adapted to be engaged with said one member so as to hold it against rotation and cause the other member to be driven, and means on said other member for causing said lever to be moved out of engagement with said one member, after it has been moved into engagement with said one member to cause rotation of said other member.

9. The invention set forth in claim 8, further characterized by said means including a lug on said other member engageable with said lever when the latter is in a position holding said one member against rotation.

10. A power lift device comprising a driver member, a pair of cooperating rotatable members adapted to be driven from said driver member, one of said cooperating rotatable members having at least one engaging portion and the other having a plurality of engaging portions, a gear secured to the driver member, one of said cooperating rotatable members having a hub portion on which the other is journaled, and one of said cooperating rotatable members having a ring gear and the other mounted rotatably on the driver member and carrying a plurality of planetary pinions meshing with the ring gear, one of said cooperating rotatable members constituting a driven member, control means normally engageable with one of the engageable portions of said driven member for holding it from rotating and upon disengagement therefrom engageable with one of the engaging portions of the other of said cooperating rotatable members for causing said driven member to be driven from the rotation of the driver member, and a crank carried by said driven member and disposed laterally outside the other cooperating rotatable member, with the latter being disposed between said crank and the driver member, whereby said crank may be rotated progressively in one direction and means responsive to a given rotation of said driven member for releasing the other cooperating rotatable member and locking said driven member against rotation.

11. A power lift device for agricultural implements and the like, comprising a driver having an axially extending section and a sun gear there-

on, a support on which said driver is journaled, said support having a portion disposed laterally outwardly of said driver, a planet gear carrier member mounted on said section and having journal portions disposed, respectively, laterally inwardly and outwardly of said sun gear, a ring gear member mounted for rotation on the laterally outer portion of said support and disposed in the laterally outer portion of said planet gear carrier member, one or more planet gears carried by said planet gear member and meshing with said sun and ring gears, control means for locking one of said members against rotation, a crank mounted on and driven by the other of said members, and a link mounted on said crank and movable thereby in a plane disposed outwardly of the outer end of said support whereby when the driven member is progressively rotated said link clears said support.

12. A power lift comprising a driver member, means for supporting said driver member for rotation, a pair of cooperating rotatable members adapted to be driven from said driver member, a gear secured to the driver member, one of said cooperating rotatable members having a hub portion on which the other of said rotatable members is journaled and one of said cooperating rotatable members having a ring gear and the other of said rotatable members being mounted rotatably on the driver member and supported thereby and carrying a plurality of planet gears meshing with the ring gear, one of said cooperating rotatable members constituting a driven member and having a crank part extending laterally outwardly of said supporting means, control means normally engageable with one or the other of said rotatable members, and a link connected with the crank portion that is disposed laterally outwardly of said supporting means, whereby said link may be shifted in alternate directions by a progressive rotation in one direction of said driven member.
